CLAIM

The ornamental design for a cleaning robot as shown and described.

DESCRIPTION

The patent or application file contains at least one drawing executed in color. Copies of this patent or patent application publication with color drawing(s) will be provided by the Office upon request and payment of the necessary fee.

1. Cleaning robot

2. Cleaning robot

3. Cleaning robot

4. Cleaning robot

5. Cleaning robot

6. Cleaning robot

1.1 to 1.8 show a first cleaning robot; 2.1 to 2.8 show a second cleaning robot; 3.1 to 3.8 show a third cleaning robot; 4.1 to 4.8 show a fourth cleaning robot; 5.1 to 5.16 show a fifth cleaning robot, wherein 5.9 to 5.16 show a variation state that the side brush and one of the mops are each shifted to an outward position, respectively; and 6.1 to 6.16 show a sixth cleaning robot, wherein 6.9 to 6.16 show a variation state that the side brush and one of the mops are each shifted to an outward position, respectively.

The portions of the design shown in the color yellow in the reproductions are for the purpose of illustrating portions of each of the first to sixth cleaning robots that form no part of the claimed design.
